FLATCAR ENDGATES

John A. Schroeder and Andrew W. Bower,
Denver, Colo.

Application May 10, 1951, Serial No. 225,586

8 Claims. (Cl. 105—380)

1

This invention relates to an end gate for railway flatcars. Loose loads, such as lumber, poles, pipe, etc., are loaded on flatcars between side stakes and the load is secured to the cars with steel straps, chains, or other tying devices. Such loads often shift longitudinally in transit so as to dangerously project beyond the extremities of the car. It is often necessary to re-tie such loose loads several times during transit.

The principal object of this invention is to provide folding terminal bulkheads or end gates for the extremities of flatcars which, when folded, will not interfere in any way with the conventional uses of the cars, but which can be raised to an elevated position to act to prevent longitudinal shifting of loose loads.

Another object of the invention is to so construct the end gate that it can be elevated to the raised position or lowered to the out-of-use position without requiring any special tools, ties, braces, or other appurtenances.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a plan view of one extremity of a railway flatcar of the cast bed type, showing the invention thereon in the folded position;

Fig. 2 is a cross-section therethrough, taken on the line 2—2, Fig. 1;

Fig. 3 is a similar cross-section, taken on the line 3—3, Fig. 1;

Fig. 4 is a side view of the car extremity of Fig. 1, illustrating the improved end gate in the elevated position;

Fig. 5 is an enlarged, fragmentary, detail section, taken on the line 5—5, Fig. 4;

Fig. 6 is a similar enlarged section, taken on the line 6—6, Fig. 5;

Fig. 7 is an inside face view of the improved end gate removed from the car;

Fig. 8 is a magnified section, taken on the line 8—8, Fig. 1;

Fig. 9 is a similar section, illustrating the end gate in the raised position; and

Fig. 10 is a similar section, taken on the line 10—10, Fig. 1, with the end gate in the raised position.

2

Only one extremity of a car has been illustrated on the drawing. It is to be understood that the other extremity thereof is similar to the one illustrated. The car illustrated is of the unitary, cast steel type, and consists of a steel bed 11 formed with integral side girders 12 and center frame trusses 13. Stake sockets 14 are cast along the side edges of the steel bed 11, and a wooden deck 15 covers the steel bed intermediate the car extremities. The invention, however, would be adaptable to other types of flat cars.

The improved, foldable end gate, designated in its entirety by the numeral 17, is positioned at each extremity of the wooden deck 15 and against raised end bolsters 16. The upper surfaces of the end bolsters 16, the upper surfaces of the folded gates, and the upper surface of the deck 15 all lie in the same horizontal plane.

The gates may have any suitable open design. As illustrated, each gate comprises a plurality of vertical and horizontal bars which define elongated, rectangular openings 18 in the gate 17. The bed 11 below the folded position of the gate is formed with a plurality of elongated, upwardly projecting bosses 19 which, when the gate is folded onto the bed 11, fill the openings 18 to form a smooth, flush upper surface, as shown in Fig. 2. The sides of the bosses 19 and the sides of the openings 18 are inclined to facilitate casting these members and to provide a wedge-like, interlocking effect when the gate is lowered.

The lower extremity of each gate is provided with a plurality of projecting hinge ears 20 which fit on each side of hinge pads 21 formed on the extremities of the bed 11. Hinge shafts 22 extend through the aligned ears and through vertically elongated shaft openings 23 in the pads to hingedly connect the gate to the bed. The sides of the bed 11 are provided with suitable receiving openings 28 through which the shafts 22 may be passed during installation.

A raised locking block 24 is formed on the bed at each side of the hinged extremity of each gate and adjacent the bolster 16. The sides of the gates are notched, as shown at 25, to fit around the blocks 24. Each of the blocks 24 is provided with a transversally-extending locking notch 26 in its upper face.

To elevate a gate, the inner extremity thereof is lifted, allowing the lower edge to tilt around the end of the bed 11 until the gate reaches its vertical position, at which time the entire gate will drop downwardly the length of the elongated openings 23, allowing the notched side edges of 55 the gate to drop into the locking notches 26, as

shown in Fig. 9, to lock the gate in the vertical position. The inner face of each bolster 16 is cut back, as shown at 38, to allow the lower edges of the gates to swing from the vertical to the horizontal position, and vice versa.

It will be noted that when the gate is in the vertical position, the lower edge thereof throughout the entire width of the gate will bear against a bearing edge 27 at the bottom of the bolster 16 to prevent the gate from falling inwardly, and the upper edge of the bolster will also bear against the gate to prevent outward movement.

While the above-described locking hinge is sufficient to rigidly support the gate in the vertical position, if still further bracing is desired, two tie rods 29 are provided. These tie rods are normally stored in vertical grooves 30 in the side members of the gate. The upper extremity of each tie rod is provided with a T-head 31 which rides in a T-shaped slot 32 in the gate.

A locking lug 33 projects into each slot 32 from one side of the latter and adjacent the vertical middle of the gate. The T-head 31 on the tie rod can be drawn down in the slot 32 as indicated in the upper broken-line position in Fig. 6, and can then be rotated around the lug 33, as indicated in the lower broken-line position, to a horizontal position below the lug, as shown in solid line in Fig. 6, to prevent upward movement of the T-head. The lower extremity of each tie rod is provided with an eye 34 which can be dropped into an eye slot 35 in the side of the bed 11 and locked therein by means of a suitable eye bolt 36.

It can be seen that the tie rods 29 effectively brace the gates 17 from movement in either direction. When not in use, the gates may be folded by withdrawing the eye bolts 36, turning the tie rods to release the T-heads 31, sliding the T-heads upwardly in their slots 32, then swinging the tie rods into their receiving slots 30, where they may be locked by passing the eye bolts 31 through locking openings 37 in the gate and through the eyes 34 to lock the tie rods in place.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. The combination with a railway flatcar having indentations in its bed adjacent its extremities, comprising: end gates; and means hinging said end gates at the extremities of said car so that they may swing from a horizontal to a vertical position, said end gates having openings corresponding to the indentations in the bed so that when folded the upper surface of the gates will align with the upper surface of said bed.

2. The combination with a railway flatcar having indentations in its bed adjacent its extremities, comprising: end gates; and means hinging said end gates at the extremities of said car so that they may swing from a horizontal to a vertical position, said end gates having openings corresponding to the indentations in the bed so that when folded the upper surface of the gates will align with the upper surface of said bed, said end gates being vertically shiftable on their hinge means so that they may be brought from a hinged condition to a locked condition by vertical movement of the gate.

3. The combination with a railway flatcar hav-

ing indentations in its bed adjacent its extremities, comprising: end gates; means hinging said end gates at the extremities of said car so that they may swing from a horizontal to a vertical position, said end gates having openings corresponding to the indentations in the bed so that when folded the upper surface of the gates will align with the upper surface of said bed, said end gates being vertically shiftable on their hinge means so that they may be brought from a hinged condition to a locked condition by vertical movement of the gate; brace rods extending from each end gate to said car, said brace rods being mounted in elongated slots in the end gates so that they may be swung into said slots when not in use; and means for locking said rods against endwise movement in said slots.

4. The combination with a railway flatcar having indentations in its bed adjacent its extremities, comprising: an end gate at each extremity of said car, said gates having a thickness corresponding to the depth of the indentations in the bed and having openings to receive said indentations when the gates are folded; hinge lugs formed on said gates at their lower extremities; hinge pads projecting from said bed intermediate said lugs; and hinge shafts extending through said lugs and through said pads.

5. An end gate for railway flatcars as described in claim 4 in which the pads are vertically slotted to allow vertical movement of said hinge shafts, and having an end bolster extending across said car adjacent each gate, the adjacent gate engaging said bolster to support said gate in the vertical position.

6. An end gate for railway flatcars as described in claim 5 having tie rods extending from the gate to said car bed.

7. An end gate construction for railway flatcars comprising: a bed at the extremity of said car, said bed being grooved to form an indented pattern; a raised bolster extending across the extremity of said car at the end of said pattern, said bed terminating in spaced relation to said bolster; hinge pads projecting from said bed toward said bolster; an end gate having an open pattern corresponding to the pattern of said bed so that it may lie in the latter; hinge ears projecting from said gate on each side of each of said lugs; and a hinge shaft extending through said ears and pads to hingedly secure said gate to said bed, said shaft being vertically movable in said pads to allow said gate to be dropped to a vertical position against said bolster for supporting said gate.

8. An end gate construction for railway flatcars as described in claim 7 having notched locking blocks between said bolster and said bed at each side of said gate to be engaged by the latter when dropped to a vertical position against said bolster.
